United States Patent Office

Des. 202,742
Patented Nov. 2, 1965

202,742

SPECTACLE FRAME FRONT

James J. Harley, Philadelphia, Pa., assignor to Optics International Corporation, Philadelphia, Pa.

Filed Oct. 14, 1964, Ser. No. 82,172

Term of patent 14 years

(Cl. D57—1)

FIG. 1

FIG. 2

FIG. 3

FIG. 4

FIG. 5

FIGURE 1 is a front elevational view of a spectacle frame front, showing my new design.

FIGURE 2 is a rear elevational view thereof;

FIGURE 3 is a top plan view thereof;

FIGURE 4 is a bottom plan view thereof;

FIGURE 5 is a side elevational thereof.

The side elevational view opposite the one illustrated in FIGURE 5 is a mirror image thereof.

The partial broken line showings of the temples are for illustrative purposes only.

I claim:

The ornamental design for a spectacle frame front, substantially as shown and described.
